UNITED STATES PATENT OFFICE.

SAMUEL G. HAGANS, OF COATESVILLE, PENNSYLVANIA.

SPACE-RETAINING DEVICE FOR CARD-INDEXES.

1,266,458.

Specification of Letters Patent. Patented May 14, 1918.

Application filed January 3, 1918. Serial No. 210,178.

To all whom it may concern:

Be it known that I, SAMUEL G. HAGANS, a citizen of the United States, residing at Coatesville, in the county of Chester and 5 State of Pennsylvania, have invented certain new and useful Improvements in Space-Retaining Devices for Card-Indexes; and I do hereby declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

This invention relates to new and useful improvements in space retaining device for card indexes and consists in the provision of a simple and efficient means for holding 20 the leaves of card indexes separated when a card is taken out for any purpose.

The invention consists of further details of construction combinations and arrangements of parts which will be hereinafter 25 fully described, and then specifically defined in the accompanying claims.

I illustrate my invention in the accompanying drawings which, with the letters of reference marked thereon, form a part of 30 this specification and in which:

Figure 1 is a perspective view of a card index showing the application of my invention.

Fig. 2 is a sectional view on line 2—2 of 35 Fig. 1.

Fig. 3 is a detail perspective view of the modified form of the drawer or casing.

Fig. 4 is a detail perspective view of one 40 of the space retaining members and rod upon which it is mounted.

Fig. 5 is a detail view of a blank of metal before being bent to form the shell.

Fig. 6 is a detail perspective view showing 45 a modified form of holding the rods in the end of the cabinet or casing, and

Fig. 7 is a detail perspective showing the manner of holding the rods in the cross-piece shown in Fig. 1.

Reference now being had to the details of 50 the drawings by letters:

K indicates an index card cabinet having the rear end thereof open and L is a cross-piece spanning the open end of the cabinet and secured to the opposite sides thereof 55 by fastening means N. Said cross-piece, a detail perspective view of a portion of which

is shown in Fig. 7 of the drawings, is provided with openings Q adapted to receive the rods S and R, each of which is provided with an annular groove adapted to receive the 60 grooved portions Q² of the latch Q', which is pivoted to said cross-piece, thereby affording means for locking the rods in place.

A sheet of metal D as shown in Figs. 4 and 5 of the drawings is provided with oppositely disposed apertured lugs D' and which plate is bent to form a cylindrical shell and mounted to have a sliding movement upon the rod R. A pin E passes through registering apertures in said lugs, 70 and F is a space retaining member which is pivotally mounted upon said pin E and has a spherical shaped end H.

It will be noted upon reference to Fig. 1 of the drawings that the inner rod S 75 serves as a means for supporting the space holding member F in convenient positions when the space holder is in use, and also as a stop for ends of cards.

In Fig. 3 of the drawings is shown a 80 modified form of the cabinet in which the two rods C, C are mounted in the end walls of the wooden cabinet A, and upon the rod adjacent to the side of the wooden cabinet a shell D is mounted having the space retaining member F pivoted thereto, while the other rod serves as a supporting means, as before described.

In Fig. 6 of the drawings I have shown a modified form of fastening rods in the 90 end T of a case A' and in which vertical grooves T' are formed in the end wall of the case to receive the ends of the rods S and R, for the reception of the latch T² which is pivoted to the end T and adapted 95 to engage said rods in the manner shown.

In use, it will be noted that when it is desired to hold the cards of the index spaced apart, the members D may be moved back and forth the full length of the cabinet or 100 casing and having a universal movement may be tilted down between any two cards to space the same apart.

Owing to the simplicity of the construction of my space retaining device, the same 105 may be easily and quickly applied to various forms of filing cabinets, drawers or boxes, either of metal or wood, and the cards may be spaced and retained equally well at the ends of the drawers as in the middle, it 110 being noted that the retaining device slides the entire length of the cabinet and when

withdrawn from between the cards, the retaining device will be out of the way. Owing to the shape of the retainers, having spherical ends, the cards will space apart a suitable distance so that the removed card may be easily slipped in place.

What I claim to be new is:

1. A card index space retaining device comprising in combination with a cabinet, a rod supported therein, a sliding member upon said rod, a space retainer pivoted to said member, and means for supporting the retainer between the cards.

2. A card index space retaining device comprising in combination with a casing, a rod supported therein, sliding members made of pieces of metal bent to form cylindrical shell portions with integral lugs projecting therefrom, space retaining members pivoted between said lugs, and having their free ends terminating in spherical portions.

3. A card index space retaining device comprising in combination with a casing, a rod supported therein, sliding members made of pieces of metal bent to form cylindrical shell portions with integral lugs projecting therefrom, space retaining members pivoted between said lugs, and having their

free ends terminating in spherical portions, and a second rod for supporting the retaining members when positioned between the cards.

4. A card index space retaining device comprising a casing one end being open, a cross-piece fastened to the open end and provided with apertures, rods passing through said apertures, means for holding the rods in place, sliding members mounted upon one of said rods, and a retaining device pivoted to said members.

5. A card index space retaining device comprising a cabinet open at one end, a cross-piece fastened to the side of the cabinet at the open end, and having apertures formed therein, rods passing through said apertures and mounted within the casing, said rods provided with circumferential grooves, a latch pivoted to the cross-piece and having a recessed edge adapted to engage said grooves of the rods.

In testimony whereof I hereunto affix my signature in presence of two witnesses.

SAMUEL G. HAGANS.
